UNITED STATES PATENT OFFICE.

GIUSEPPE TESTA, OF NEW YORK, N. Y., ASSIGNOR TO ISIDORE ORLANDO DE PASS, OF NEW YORK, N. Y.

FIREARM.

1,258,378.

Specification of Letters Patent.

Patented Mar. 5, 1918.

Application filed August 13, 1917. Serial No. 185,841.

To all whom it may concern:

Be it known that I, GIUSEPPE TESTA, residing at No. 209 East 116th St., in the borough of Manhattan, city, county, and State of New York, have invented certain new and useful Improvements in Firearms, of which the following is a full, clear, and exact specification.

This invention is particularly directed to improvements in firearms of the class described in Letters Patent granted to me July 4, 1899 and bearing Number 628,130.

The primary object of this invention is the devising of a firearm of the type referred to, in which all of the cartridges may be fired at the same time, or if desired, only a part may be fired at one time and another part at a subsequent time.

Referring to the drawings forming part 20 of this specification—

Figure 1 is a perspective view of a revolver comprising my improvements.

Fig. 2 is a plan view of same.

Fig. 3 is a detail view of the firing mechanism with certain parts removed for more clearly revealing the interior mechanism.

Figs. 4 and 5 show the cartridge holder, Fig. 5 being the cartridge supporting plate and Fig. 4 being the retaining cover for same.

Fig. 6 is an end view of the plate with the cartridges assembled.

Fig. 7 shows a cartridge partly broken away to give a clearer understanding.

Fig. 8 is a section through the broken line 8—8 of Fig. 5, and Fig. 9 is a section through the line 9—9 of Fig. 2.

In the preferred embodiment the barrel 1 is composed of a cluster of ten separate bores 40 and is pivotally secured at 2 to the stock 3 and maintained in firing position by the locking pin 4, all of which resembles in the main the corresponding parts disclosed in my patent above referred to. In the present instance, however, the locking pin 4 is provided with a thumb actuated latch 5 projecting from the side thereof, which is adapted to engage a groove 6 formed in the stock 3 for firmly securing the pin in its locked position. To make the latch more secure, I provide a catch 5' in the form of a spring actuated lever, which has its inner end adapted to engage the lip 6' formed in the stock, and is released therefrom by de-

pressing the outer end simultaneously with 55 the forcing of the latch piece 5 upward. The pin 4 is adapted to rotate in its retaining bore in the socket so that the latch may be raised to free it from the socket, whereupon the pin 4 is automatically thrust rearward in the usual manner for releasing the barrel to permit the joint to be broken, as seen in Fig. 1. This enables the discharged cartridges to be removed and a fresh charge to be inserted, the cartridge plate being simultaneously thrust outward for better facilitating the manipulation of the cartridges.

Referring now to the mechanism enabling the cartridges to be fired all at the same time or by separate groups as desired, I 70 provide a breech plate 8 carrying the firing pins 9, one for each group of the cartridges A. In the present instance as only two groups are shown but two firing pins are needed.

There are two hammers 10—10, one for each firing pin and as their controlling mechanism is similar a description of one will suffice. The hammer 10 is pivoted to the stock by the pin 11 and is somewhat 80 in the shape of a bellcrank, the forward end serving as the hammer proper for striking the firing pin, while the rear end is pivoted to an arm 12, which engages one end of the bent spring 13, the other end being supported by the fixed pin 14 and extended to abut against the lug 15 on the hammer to serve as a stop for limiting the movement of the latter when released. The pin 11 which is fixed to the hammer has the finger 90 actuated arm 16 secured thereto whereby the hammer may be thrown backward against the tension of spring 13 to cocked position.

A single trigger 17 is provided for controlling both of the hammers. This trigger is pivotally secured to the stock as at 18 and has the plate 19 fixed thereto. At each side of this plate a toothed catch 20 is provided for engaging the teeth 21 formed on the hammer, and a spring 22 serves to 100 maintain the respective teeth in engagement. It will be observed when the hammer is withdrawn to cocked position the tooth 20 engages a tooth 21 in the hammer and the latter remains in cocked position 105 until the trigger is pulled against the tension of spring 21 to release the engagement of the teeth whereby the spring 13 reacts to

force the hammer against the firing pin and thus fire the group of cartridges A. It will further be observed that if but one hammer is set to cocked position the trigger will only 5 operate this hammer, after which the other hammer may be similarly set and operated for firing the second group of cartridges. On the other hand, if both hammers are cocked at the same time then by a single 10 pulling of the trigger both will be released and all the cartridges will be fired simultaneously.

A further important object of my invention is the devising of a cartridge holder 15 whereby either of the groups of cartridges may be fired without exposing the cartridges of the other group to the danger of being unintentionally fired. In the preferred embodiment the plate 7 is provided with the 20 holes 23 through which the cartridges A protrude, the same being arranged in groups consisting in the present instance of five cartridges which are fired at the same time. The holes are provided with the shoulders 25 to engage the heads 25 of the cartridges to secure them within the plate. The plate is provided with a chamber 26 to which is secured a percussion cap 27. One of these is provided for each group of cartridges 30 and is preferably disposed more or less centrally of the group. The percussion cap is exposed through a suitable orifice in the cover in position to register with the firing pin 9 to be fired thereby when the trigger is 35 pulled. Grooves 28 are provided connecting the cap with the cartridges and the cartridges are provided with holes 29 in alignment with these grooves whereby they are fired upon the firing of the cap. The 40 cartridges are further provided with lugs 30 which engage with slots 31 formed in the holes 23 in order to insure a positive alignment of the holes 29 with the grooves 28. The plate is moreover provided with a hole 45 32 for permitting the lock bolt 4 to pass therethrough when locking the barrel. A cover 33 is provided with a marginal flange 34 which is adapted to fit snugly about the plate 7. Holes 35 are provided in the cover 50 to register with the caps in order to leave them exposed in line with the firing pins, as already mentioned. In order to confine the flash of powder in the grooves 28, I provide tongues 36 radiating from the holes 35 55 and adapted to fit in the grooves 28 but leaving in the base thereof sufficient room for the flash. To further prevent any possibility of the flash of powder from the cap of one group from passing over to the other 60 group I provide a shoulder 37 about the hole 32 and a groove 38 extending across the plate to divide it in halves. The cover 33 is correspondingly provided with a flange 39 and bead 40 disposed respectively to be engaged by the shoulder 37 and groove 38

thereby providing a partition wall separating the two groups of cartridges.

Having thus described my invention I claim—

1. In a firearm of the class described, a 70 barrel composed of a plurality of spaced bores for receiving cartridges, a breech, a plurality of firing pins supported by said breech directly opposite the space between the bores adapted to fire selective groups of 75 cartridges, a hammer for each of the firing pins, means for bringing each hammer to cocked position independently of the other hammer, and a trigger adapted to release the hammers that are at cocked position simultaneously 80 by a single operation.

2. In a firearm of the class described, a barrel composed of a plurality of spaced bores for receiving cartridges, a breech, a firing pin supported by said breech directly 85 opposite a spacing wall of said bores adapted to fire a plurality of cartridges simultaneously, and means for actuating the firing pin.

3. In a firearm of the class described, a 90 stock, a barrel pivoted thereto, a locking pin having longitudinal movement in the stock for securing the barrel in firing position, a latch secured to the locking pin adapted to be turned into a receiving groove of the 95 stock when the pin is in locked position, a lip formed on the stock and a catch secured on the latch for engaging with the lip and holding the latch in locked position.

4. In a firearm of the class described, a 100 stock, a barrel pivoted thereto, a locking pin having longitudinal movement in the stock for securing the barrel in firing position, a latch secured to the locking pin adapted to be turned into a receiving groove of the 105 stock when the pin is in locked position, and means for securing the latch in said groove.

5. In a firearm of the class described, a 110 stock, a barrel pivoted thereto, a locking pin having longitudinal movement in the stock 110 for securing the barrel in firing position and a latch secured to the locking pin adapted to be turned into a receiving groove of the stock when the pin is in locked position.

6. A cartridge holder comprising a plate 115 having a plurality of spaced holes for receiving a group of cartridges, a cover for the plate, and means for retaining a percussion cap in the space between the bores adapted to fire all the cartridges simultaneously. 120

7. The combination of a cartridge holder comprising a plate having an orifice and a cover for said plate, a percussion cap secured in the holder, a cartridge projecting through said orifice having a hole in the wall thereof, and a lug engaging a groove in the holder for positioning the said hole in the cartridge in a position facing said percussion cap. 125

8. The combination of a cartridge holder comprising a plate having groups of orifices 130

for receiving groups of cartridges, the orifices of each group being connected by grooves formed in the plate, a cover for said plate, a partitioning wall between the plate and cover for separating the said groups of orifices, and means for retaining a percussion cap for each group of orifices.

9. The combination of a cartridge holder comprising a plate having a plurality of orifices and cover for said plate, a percussion cap secured in the holder and having its head exposed through an orifice in said cover, and a plurality of cartridges projecting through said orifices, each of the car-

tridges having a hole in its wall disposed in 15 said holder.

10. In combination, a cartridge, a holder therefor, a percussion cap supported by the holder, a confined passageway in the holder connecting the percussion cap directly with 20 and terminating at the cartridge for directly firing said cartridge, the cartridge being provided with a hole in its side wall opening in said passageway.

This specification signed this 11th day of 25 August, 1917.

GIUSEPPE TESTA.
